UNITED STATES PATENT OFFICE

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MECHANICAL MOVEMENT.

1,404,753.

Specification of Letters Patent. Patented Jan. 31, 1922.

Application filed July 29, 1918. Serial No. 247,215.

To all whom it may concern:

Be it known that I, FREDERICK M. FURBER, a citizen of the United States, residing at Revere, in the county of Suffolk and State 5 of Massachusetts, have invented certain Improvements in Mechanical Movements, of which the following description, in connection with the accompanying drawings, is a specification, like reference characters on the 10 drawings indicating like parts in the several figures.

This invention relates to mechanism for converting rotary movement into oscillatory movement, and, while primarily intended 15 for use in edge-setting machines, is also useful in other classes of machines.

One of the objections to edge-setting machines of the type in which the tool is rapidly vibrated to burnish the sole edge 20 while it is held against the tool by the workman, is the excessive amount of vibration of the entire machine, which causes rapid wear of the machine parts, imposes wearying strains upon the workman, and produces 25 much noise. Excessive vibration is due to many causes, among which is the high speed at which the driving member must be caused to run in machines where such member rotates once for every complete oscillation of 30 the tool-carrying shaft. The foregoing and many other objections of mechanisms as heretofore employed for operating edge-setting tools where a high vibratory speed is produced in a driven member from a rotary 35 driving member, are overcome by the present invention, in which a compact, efficient, and relatively simple arrangement of parts is employed.

A requirement which it has been found 40 necessary to meet in the design of edge setters of the best quality is that of flexibility in adjustment. It is necessary that the oscillatory speed of the tool and that the throw of the tool be adjustable to meet the preferences of individual manufacturers with regard to different classes of work.

An important feature of the invention is comprised in an organization wherein the driving member and driven member lie one 45 within the other and are preferably mounted one on the other and concentrically arranged, and movement is transmitted from the former to the latter through devices which include gearing. This combination

permits the use of gears of such ratio as to 55 produce the desired amplitude and frequency of oscillation in the driven member carrying the tool without varying the speed of rotation of the driving member. At the same time, the relation between the driving 60 and driven members makes the mechanism very compact and absorbent of the shocks due to unbalanced moving parts. The reactions of the members are balanced against each other to a certain extent, instead of being 65 both transmitted to the frame of the machine. The stresses reaching the frame and therefore causing vibration are thereby diminished.

Other features of the invention consist in 70 certain important details of construction and combinations of parts which will be better understood from the following description, and which are more particularly pointed out in the claims.

In the drawings, wherein an embodiment 75 of the invention is illustrated,

Fig. 1 is a view in side elevation, partly sectional.

Fig. 2 is a view in elevation, partly sectional, of the oil reservoir taken in the direction of the arrow, Fig. 1, the parts being broken away to show the gearing and associated elements.

Fig. 3 is a detail view showing the oil 80 reservoir inspection window.

Fig. 4 is a view in vertical section of the same part, and

Fig. 5 shows a pair of gears having a different ratio.

The shaft 2 oscillates in bearings sustained by the machine frame 1, one of said bearings being referred to by the numeral 4. The shaft 2 carries two loose pulleys 6, 8, the former being an idler and the latter having a flange 10, and being secured by suitable means, as screws 9, to a gear 12 which rotates on the shaft 2 with the pulley. A bushing 14, which is fixed in the frame, surrounds the shaft 2, the bushing having a 95 flange 16 whose outer face is adjacent to the inner wall of a drum or casing 21, the open end of which is secured to and closed by the flange 10. The flange 16 of the bushing has an extension 17 provided with a split bearing within which is clamped a stud 18 by a screw 19. On this stud is rotatably mounted a gear 20 meshing with the gear 12. The 100 105

gear 20 has an eccentric 22, which is secured rigidly thereon and lies between said gear and the extension 17. The eccentric seats in a rectangular block 24 which is embraced by 5 a fork 26, the latter being secured rigidly to the shaft 2.

The block 24 slides in the fork as in a guideway and serves to transmit the movements of the eccentric to the fork in the 10 form of oscillations, which movements are in turn applied to the tool-carrying shaft 2. As the gear 12 is rotated by the pulley 8, the rotatory movement of the latter is, through the described connections, converted into oscillating motion of the shaft 2. The gear ratio between the gears 12 and 20 is, in the 15 example illustrated, 2-1, so that for each rotation of the pulley, four oscillatory movements are imparted to the tool carrying shaft, and the vibrations of the burnishing tool are accordingly twice as many as would be the case if the gear 20 were rotated once for each rotation of the pulley 8.

It will be apparent that by substituting 25 other gears (see Fig. 5) for those shown, in which the gear ratio is different, the speed of oscillation may be varied at will. It is also apparent that the amplitude of the vibrations, or extent of "throw" of the burnishing tool can be varied by changing the 30 amount of eccentricity of the eccentric 22.

The means for transmitting movement 35 between the driving member, or pulley 8, and the driven member, or shaft 2, and which comprises the gears 12 and 20, the eccentric and other connections, are all enclosed by the casing 21 and run in oil in said casing. This insures complete lubrication 40 of the essential working parts, and by minimizing friction keeps them in good running condition, and increases their durability.

The flange 10 is provided with an internally screw-threaded opening which receives a threaded bushing 28, provided with 45 a flange for seating upon the outside of the flange 10, and a transparent window 30 for inspecting the condition of the oil within the casing.

A driving belt 31 transmits power from 50 any suitable source to the loose pulley 6, and a belt shifter 32 may conveniently be employed for shifting the belt from the loose pulley 6 to the driving pulley 8, and vice versa, for starting and stopping the machine 55 at will.

It is to be observed that the mechanism for 60 converting the rotary movements of the driving pulley into oscillating movement of the tool-carrying shaft is exceedingly compact, simple, and efficient, in that the driving member and the driven member are concentrically arranged one within the other. The arrangement referred to reduces friction 65 as compared with other known devices and, moreover, permits of the use of simple

geared connections whose gear ratios may be selected, and varied at will, in order to effect the required number of oscillatory movements in the burnishing of the tool for each complete rotation of the driving member. 70 It is thus possible to run the pulley 6 at a comparatively low speed and to secure high vibratory speeds by a proper gear ratio. The efficiency of the edge-setting operation is greatly enhanced by rapid vibration, as 75 high as, for example, 7000 oscillations per minute. This may be easily secured by a pulley rotating at 900 R. P. M. The belt velocity is correspondingly slower and the difficulties due to vibration are relieved, since 80 the only unbalanced parts in the machine are the eccentric 22 and the fork 26, which are so light in comparison with the mass of the uniformly rotating parts that their unbalance 85 effect is practically masked.

The mounting of all the pulley and heavy 90 rotating parts upon the oscillating shaft makes the machine very compact which is of great importance in machines of this kind. It gives the pulley 6 a strong support at 90 each side without requiring another heavy shaft. It permits the assembling of the entire transmission mechanism in a simple compact oil casing.

Having thus described my invention, what 95 I claim as new and desire to secure by Letters Patent of the United States is:

1. In a mechanism of the character described, the combination with a rotary driving member, of a shaft supported within 100 said member, connections including an eccentric and toothed gearing between said driving member and shaft for converting rotary motion of the driving member into oscillatory motion of the shaft, and a casing 105 mounted on the driving member and rotating therewith, for containing oil enclosing said connections, the shaft extending through the casing and having a bearing on both sides thereof.

2. The combination with a rotary driving member, of a shaft supported concentrically within said member, a gear carried by said member, a second gear in mesh with the first-named gear, an eccentric carried by said second gear, and connections between said eccentric and shaft, said shaft extending continuously through said member and said first-named gear, and bearings for said shaft located on opposite sides of said gears and 110 eccentric, said parts operating to convert the rotary motion of said driving member into oscillatory motion of said shaft.

3. The combination with a rotary driving member, of a shaft supported concentrically 125 within said member, a flanged bushing surrounding said shaft and having an extension, a stud clamped to said extension, an eccentric on said stud, gearing connecting said driving member and eccentric, a recip- 130

rotatory block on said eccentric, and a fork fast to said shaft and embracing said block.

4. The combination with a rotary driving member, of a continuous shaft supported concentrically within said member, a stud supported eccentrically with reference to said member, an eccentric on said stud, interchangeable gearing between said driving member and eccentric, bearings for said

shaft on opposite sides of said gearing and eccentric, and connections between said eccentric and shaft co-operating with said eccentric to convert rotary motion of the driving member into oscillatory motion of the shaft.

In testimony whereof I have signed my name to this specification.

FREDERICK M. FURBER.
